US00D637988S

(12) **United States Design Patent**
Jinkinson

(10) **Patent No.:** **US D637,988 S**
(45) **Date of Patent:** **** May 17, 2011**

(54) **COMMUNICATION DEVICE**

(75) Inventor: **Nick A Jinkinson**, Reading (GB)

(73) Assignee: **Motorola Mobility, Inc.**, Libertyville, IL (US)

(**) Term: **14 Years**

(21) Appl. No.: **29/366,772**

(22) Filed: **Jul. 29, 2010**

(51) **LOC (9) Cl.** **14-03**

(52) **U.S. Cl.** ..... **D14/138 AA**

(58) **Field of Classification Search** ..... D14/138 AA, D14/138 AB, 138 R, 138 AD, 138 AC, 138 G, D14/341, 345, 346, 203.4, 203.7, 203.1, 203.3, D14/496; 455/575.3, 575.1, 575.4, 556.2; 379/433.01, 433.04, 433.1, 433.13; D21/517

See application file for complete search history.

(57) **CLAIM**

The ornamental design for a communication device, as shown and described.

DESCRIPTION

FIG. 1 is a front perspective view of an ornamental design for a communication device;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown throughout the views that are immediately adjacent to the shaded areas and define unshaded regions, represent the bounds of the claimed design, while all other broken lines are directed to environment and are for illustrative purposes only; the broken lines form no part of the claimed design.

1 Claim, 6 Drawing Sheets
